UNITED STATES PATENT OFFICE.

ISAAC C. SHALKOP, OF PHILADELPHIA, PENNSYLVANIA, ASSIGNOR TO THE DE LUXE
BRUSH COMPANY, OF WILMINGTON, DELAWARE, A CORPORATION OF DELAWARE.

DISPENSING DEVICE.

Application filed June 9, 1922. Serial No. 567,069.

To all whom it may concern:

Be it known that I, ISAAC C. SHALKOP, a citizen of the United States, and a resident of Philadelphia, in the county of Philadelphia and State of Pennsylvania, have invented an Improvement in Dispensing Devices, of which the following is a specification.

My invention relates to improvements in dispensing devices of the character in which the liquid or semi-liquid material to be dispensed is contained within a container situated within a shell or handle and in which the expulsion of the said material is effected by simultaneous rotation of the shell and container in the same direction.

I have shown the invention as embodied in a shaving brush in which the container is of the collapsible type, but it is to be understood that it may be employed in connection with constructions in which the dispensing means is not embodied in a shaving brush and also in which the container is not of the collapsible type.

The principal object of the invention is to provide a new and novel means for causing the container to rotate with the shell within which it is inclosed when said shell is rotated.

A further object is to provide a detachable cap portion of the shell with means which is adapted to engage the container so that when the shell is rotated the container will be caused to rotate therewith.

Other objects and advantages of the invention will be pointed out in the detailed description thereof which follows or will be apparent from such description.

In order that the invention may be readily understood and its practical advantages fully appreciated, reference may be had to the accompanying drawing in which one form of mechanical embodiment thereof is depicted, but it will be understood that changes in the details of construction may be made within the scope of the claims without departing from the said invention.

In the drawings:

Fig. 1 is a view partly in side and partly in longitudinal central section of a shaving brush provided with the invention;

Fig. 2 is a view in longitudinal section of the outer or lower portion of the container for the material to be dispensed which is adapted to be situated within the

hollow handle or shell of the device, the said view also indicating indentations caused by the means for connecting a part of the shell and the said container together to cause them to rotate in unison when the shell is rotated;

Fig. 3 is a bottom plan view of the said container; and

Fig. 4 is a transverse sectional view of the cap portion of the shell taken on the line 4—4 of Fig. 1.

Referring to the drawing: 1 designates the bristles of a brush, such as a shaving brush, and 2 the head of said brush which is adapted to be secured to the inner or upper portion of the handle of the structure from which the material is adapted to be dispensed. The handle portion comprises the main or body portion 3 consisting of a tubular shell, the lower or outer end of which is screw-threaded, as indicated at 4, with which the upper screw-threaded portion 5 of an end cap 6 is adapted to be engaged.

The tubular shell 3 is provided with a circular bead-like portion 7 with which the inner or upper end of the cap 6 is adapted to contact. This bead-like portion projects outwardly beyond the outer surface of the upper screw-threaded end portion 5 of the cap so that any water which may run down the side of the tubular shell portion 3 will not be apt to pass in between the portion 5 of the cap and the adjacent portion 4 of the shell 3.

Situated within the shell or handle comprising the parts 3 and 6 is a collapsible container 10 the upper closed end 11 of which is relatively thick and is provided with a projection 12. A screw-threaded opening 13 extends through the upper end 11 of the container and through the projection 12. A screw-threaded tube 15 carried by the inner upper end portion of the structure extends through said opening. The screw-threads upon the said tube 15 and within the opening 13 are left handed so that upon turning the container to the right the inner end thereof moves downwardly to force the material within the said container into the tube 15 and outwardly into the bristles 1.

The outer end of the container is closed by means of a closure having a thickened central projecting portion 20 which is

adapted to fit into a centrally situated depression 21 upon the inner side of the outer end of the cap 6. Such depression is formed by pressing the metal outwardly so that a corresponding projection appears on the outer side of said end. The exterior side of the outer end of the cap 6 is provided with an annular projecting portion 22 the inner side of which constitutes a groove upon the interior side of said end of like shape and contour. Interposed between the said projecting portion 22 and the central outwardly extending portion 23 of the outer end of the cap is an annular groove or depression 24. Situated at intervals within and extending transversely of the interior groove formed by and in opposed relation to the projection 22 are wedge-shaped web portions 25 which are adapted to engage and bite into the flange-like lower end portion 28 of the container 10. The inner surface of the depression 21 is provided with pointed projections 30 which projections are adapted to engage and bite into the thickened portion 20 of the end of the container 10 when such container is placed within the hollow shell or handle and the cap 6 screwed into position thereover. Simultaneously the edges of the wedge-shaped webs 25 engage the edges of the flange-like portions 28 and bite into the same.

It will be understood that in order that the pointed projections 30 and the wedge-shaped webs 25 may bite or cut into the portions of the container with which they engage the material of the latter must be of soft metal, such as tin foil or the like. In screwing the cap 6 up against the outer end of the container it will be understood that when the points of the projections 30 and the edges of the wedge-shaped webs 25 engage with the adjacent opposing portions of the bottom of the container the latter will thereafter turn with the cap and that as the latter is screwed down upon the portion 3 of the shell the said pointed projections and wedge-shaped webs will be caused to cut into or indent the said portions of the said container.

It will be apparent, therefore, that I have provided means whereby the outside shell structure of the device is adapted to be positively connected with the container so that upon rotation of said shell with respect to the head or top portion of the structure the container is positively rotated therewith. In this way a positive means is provided for effecting rotation of the container

10 to thereby insure that the liquid or semi-liquid material therein will be expelled therefrom through the tube 15.

Having thus described my invention what I claim and desire to secure by Letters Patent is:

1. A device for dispensing liquid or semi-liquid materials, comprising a shell adapted to receive a container for the material to be dispensed, which shell has a cap at its outer end which is provided with projections which are adapted to engage the said container whereby when the said shell is rotated the said container is rotated, and means whereby when the said container is rotated in one direction the material there- 75 in is caused to be discharged.

2. A device for dispensing liquid or semi-liquid materials, comprising a shell adapted to receive a container for the material to be dispensed, which shell has a cap at 80 its outer end which is provided with projections which are adapted to engage the said container whereby when the said shell is rotated the said container is rotated, and a discharge tube which extends into the 85 said container with which the said container is in adjustable engagement whereby when the said shell and container are rotated in one direction collapsing of the said container is effected to cause the discharge of 90 the said material therefrom.

3. A device for dispensing liquid or semi-liquid materials, comprising a shell adapted to receive a container for the material to be dispensed, which shell comprises a cap 95 having a central depression upon its inner side into which a central projection upon the outer end of the said container projects and the bottom of which depression is provided with projections which engage the 100 said projection upon the container, and the said cap being provided with an annular groove upon its inner side across which projections extend, which projections are adapted to engage a peripheral flange upon 105 the said container, engagement of the first and second named projections with the said container being adapted to cause the said shell and container to rotate in unison, and means whereby when the said shell and container are rotated in one direction the material to be dispensed is discharged from the 110 said container.

In testimony that I claim the foregoing as my invention I have hereunto signed my 115 name this 8th day of June, 1922.

ISAAC C. SHALKOP.
